UNITED STATES PATENT OFFICE.

MATTHEW ARNOLD, OF SAN JOSE, CALIFORNIA.

AMALGAMATING-MACHINE.

1,127,845.

Specification of Letters Patent.

Patented Feb. 9, 1915.

Application filed September 15, 1913. Serial No. 789,812.

To all whom it may concern:

Be it known that I, MATTHEW ARNOLD, a citizen of the United States, residing at San Jose, in the county of Santa Clara and State of California, have invented a new and useful Improvement in Amalgamating-Machines, of which the following is a specification.

My invention relates to an improvement 10 in amalgamating machines, and the objects of my invention are, first to provide an amalgamating machine that does not require the use of amalgamating plates; second, to provide an amalgamating machine that will 15 separate all of the gold from the pulp supplied to it; third, to provide an amalgamating machine that will effectually prevent any loss of mercury or amalgam; fourth, to provide an amalgamating machine that can 20 be attached to any ore pulverizing machine.

Further objects and advantages will appear in the following description.

I attain these objects by the mechanism illustrated in the accompanying drawings, 25 in which—

Figure 1 is a front elevation of my amalgamating machine, parts being broken away. Fig. 2 is a plan view of my amalgamating machine. Fig. 3 is a vertical cross 30 section on line "A—A" of Fig. 2.

Similar numerals refer to similar parts throughout the several drawings.

Referring to the drawings, 1 is a bored cylindrical casting which constitutes the 35 main body of my machine; said cylinder 1 being supported by a member 2, which is preferably an integral part of said cylinder and provided with a flange 3 by which said cylinder 1 is bolted securely to a support 40 constructed for that particular purpose, or directly to an ore pulverizing machine. Near the upper end of said cylinder 1 are provided two circular inlets 4 through which the pulp is admitted to cylinder 1; 45 said inlets 4 are provided with offsets 5 to which a flanged inlet pipe 6 may be fastened by stud bolts 7. Cylinder head 8 is securely bolted to said cylinder 1 by bolts shown at 9, said cylinder head 8 having a drip ring 50 cast on its upper surface as shown at 10, and a hole bored through its center to permit the free working of piston rod 11. Said piston rod 11 is preferably made of bronze and is threaded on its upper end to engage the 55 bored and threaded arm 12 of guide 13 and is securely held in place in said arm 12 by

collar nuts 14, one on each side thereof. Said guide 13 is provided with flanges 15, and pinion 17 which travels in a vertical direction in guide slot 16 when power is applied to pinion 17 which is an integral part of guide 13. Said guide slot 16 is formed by two vertical, parallel steel bars 18 which are preferably an integral part of cylinder head 8. Near the lower end of said cylinder 1 is 60 a shouldered flange 19, preferably an integral part of said cylinder 1 and strengthened and supported by braces 20, for this shouldered flange 19 supports the entire weight of the amalgamating receptacle and 65 its contents. Suspended in approximately the center of said cylinder 1 and projecting a distance below the lower edge thereof, is a bell shaped deflector, the same being closed at the bottom and top, as shown at 21; said 70 deflector being suspended by means of a horizontal bar 22, which is fastened to the inner circumference of said cylinder 1 by screws 23. Piston rod 11 has a valve 24 attached near its lower end and a rod 25, of 75 smaller diameter than piston rod 11, depending from the center of the under surface of said valve 24; said rod 25 being of sufficient length to permit the valve to open a distance on the upstroke of said piston rod 11, and 80 threaded on the end to receive a threaded nut 26, and pierced to receive a steady pin 27; said rod 25 passes through a vertical hole 28 in bar 29, said bar 29 being fastened at both ends to the inner circumference of 85 piston head 30 said piston head 30 being hollow and having a valve seat 24^a on its upper edge to receive valve 24, and a plurality of grooves in its outer circumference as shown at 31 to receive a water-tight packing. 90 This packing may be made of steel spring rings or any other suitable packing that will prevent water from passing between said piston head 30 and the inside of cylinder 1 on the down stroke of piston head 30 when valve 24 is closed down on valve seat 24^a. At the extreme lower end of cylinder 1, and preferably an integral part thereof, is an outward diverting flange 1^a. This flange 1^a is for the purpose of diverting the 95 pulp through the mercury on the down stroke of piston head 30 and thus accomplishing two desired results; first, it causes said pulp to be discharged in a wide, comparatively thin, circular stream, thus permitting practically all of said pulp to come 100 in contact with said mercury; second, it

causes said pulp to pass vertically upward through the center of the body of mercury, thus allowing said mercury to act upon said pulp on all sides.

- 5 The amalgamating receptacle 32 is securely bolted to shouldered flange 19 by bolts 33, and has two handles 34 securely bolted near the upper edge of its inner wall, for the purpose hereinafter described.
- 10 The lower part of amalgamating receptacle 32 is hemispherical in shape, and has a circular orifice in the lower part thereof. This orifice is tapped and threaded from both its inner and outer ends so that it may receive
- 15 a plug from either direction as shown at 35 and 36. The drawing shows a plug screwed into position from the inside at 37. The upper portion of amalgamating receptacle 32 is circular in plan and has a waste chamber 32^a and a discharge chute as shown at 38, and an inner partition wall 39 which is preferably an integral part of receptacle 32, and is provided with openings 40 which are the discharge openings from the amalgamating chamber 41. Immediately below said openings 40 is a flange flaring inwardly as shown at 42 for the purpose hereinafter described. 43 is an endless pipe encircling said cylinder 1, having a continuous slot cut
- 20 in its lower side as shown at 44 and supplied with water under pressure through pipe 43^a. 45 shows a vertical hole bored through a boss cast on the upper surface of said shouldered flange 19, and through said shouldered flange 19, by which mercury is admitted to said amalgamating chamber 41. A plug is shown at 46 for closing the same.
- 25 47 is a glass gage set in cement and connected to said amalgamating chamber 41 by
- 30 a passage 48; this passage 48 is bored through from the outside and the outer portion of the opening, shown at 49, is then plugged.
- 35 50 indicates the point on the gage which shows when sufficient mercury has been placed in the amalgamating chamber.
- 40 51 indicates the point on the gage to which the mercury has advanced when so filled with amalgam that it should be removed for reduction.

The action of my machine is as follows: The amalgamating chamber 41 is filled with mercury to the point 50 on the gage. Pulverized ore mixed with water is admitted

45 to cylinder 1 through inlet 4. As piston rod 11 ascends it opens the valve 24 until the nut 26 strikes the bar 29, when the piston head 30 is drawn upward allowing the pulp to flow downward through the valve

50 opening until it reaches the surface of the mercury. As the direction of the piston rod is reversed the valve descends to its seat 24^a on the piston head, when the piston head is forced downward and the pulp beneath it is

55 forced downwardly and outwardly through

the comparatively narrow space between the deflector 21 and outward diverting flange 1^a of cylinder 1, and through the mercury where the amalgam is formed, the residue passing off through openings 40 into the waste chamber 32^a, and discharged at the chute 38. If at any time the pulp does not contain sufficient water, then water under pressure is forced through the pipe 43^a into pipe 43, and through the slot 44, and against the outer surface of cylinder 1, which, together with flaring flange 42 gives it an eddying motion which effectually dilutes the pulp and allows every particle of gold to settle in the mercury because of its greater specific gravity. The specific gravity of gold being about 19.28, and of mercury about 13.62, nearly all of the gold will be separated from the pulp during the passage of said pulp through the mercury, and the eddying motion described above will effectually extract the remainder. When sufficient amalgam has formed to raise the level of the mercury to the point 51, hoisting chains are attached to handles 34, the bolts 33 are removed and the entire amalgamating receptacle is lowered, whereupon plug 37 can be removed and the amalgam drawn off into another receptacle, the plug replaced and the amalgamating receptacle put back into position. If the plug is screwed into place from the outside instead of from the inside as shown, then the amalgam may be removed without detaching the amalgamating receptacle from the main portion of the machine.

Having thus described my invention, what I claim as new and desire to secure by Letters Patent, is—

1. In an amalgamating machine the combination of a cylindrical casting having a supporting member, a shouldered flange adapted to fasten an amalgamating receptacle thereto, a bell shaped deflector closed at the bottom and top thereof, a horizontal bar fastened to the inner circumference of said cylindrical casting to which said bell shaped deflector is fastened, an outwardly projecting diverting flange at the lower end of said cylindrical casting and an amalgamating receptacle hemispherical in shape attached to said shouldered flange, the upper portion thereof being circular in plan having a waste chamber and a discharge chute and an inner partition wall having openings, as shown and described.

2. In an amalgamating machine the combination of a cylinder having a supporting member, a shouldered flange adapted to fasten an amalgamating receptacle thereto, a deflector, a horizontal bar fastened to the inner circumference of said cylinder to which said deflector is fastened, an outwardly projecting diverting flange at the lower end of said cylinder, and an amal-

mating receptacle attached to said shouldered flange, said amalgamating receptacle having an inwardly flaring flange, substantially as shown and described.

5. 3. In an amalgamating machine, the combination of a cylinder having a supporting member, a shouldered flange adapted to fasten an amalgamating receptacle thereto, a bell shaped deflector closed at the bottom 10 and top thereof, a horizontal bar fastened to the inner circumference of said cylinder to which said bell shaped deflector is fastened, an outwardly projecting diverting flange at the lower end of said cylinder, 15 and an amalgamating receptacle hemispherical in shape attached to said shouldered flange said amalgamating receptacle being provided with a closable orifice in the lower part thereof as and for the purpose de- 20 scribed.

4. In an amalgamating machine, the combination of a cylinder having a supporting member, a shouldered flange, a bell shaped deflector closed at the bottom and top there-

of, a horizontal bar fastened to the inner 25 circumference of said cylinder to which said bell shaped deflector is fastened, an outwardly projecting diverting flange at the lower end of said cylinder, means for admitting pulp to said cylinder, means for 30 forcing said pulp out of the lower end of said cylinder, and an amalgamating receptacle hemispherical in shape attached to said shouldered flange, said amalgamating receptacle being provided with a closable 35 orifice in the lower part thereof and having a waste chamber in the upper portion thereof and a discharge chute and an inner partition wall having openings as and for the purpose described. 40

In testimony whereof I have signed my name to this specification in the presence of two subscribing witnesses.

MATTHEW ARNOLD.
